UNITED STATES PATENT OFFICE.

EDITH E. LEVETT, OF NEW YORK, N. Y.

DESIGN FOR A COVERING FOR DOLLS, CALENDARS, PADS, BLOTTERS, CARDS, OR SIMILAR ARTICLE.

52,802.

Specification for Design.

Patented Dec. 24, 1918.

Application filed July 1, 1918. Serial No. 242,965. Term of patent 14 years.

To all whom it may concern:

Be it known that I, EDITH E. LEVETT, a citizen of the United States, residing in the city of New York, borough of Manhattan, in the county and State of New York, have invented a new, original, and ornamental Design for a Covering for Dolls, Calendars, Pads, Blotters, Cards, or Similar Articles, of which the following is a specification, reference being had to the accompanying drawing forming part thereof.

The figure is a face view of a covering showing my new design.

I claim:

The ornamental design for a covering for dolls, calendars, pads, blotters, cards, or similar article, as shown.

EDITH E. LEVETT.
